ROTATING EXPLOSION-ENGINE.

No. 895,653.

Specification of Letters Patent.

Patented Aug. 11, 1908.

Application filed September 12, 1906. Serial No. 334,327.

To all whom it may concern:

Be it known that I, ROY CLIFTON MARKS, a citizen of the United States, residing at San Diego, in the county of San Diego and State 5 of California, have invented a new and useful Rotating Explosion-Engine, of which the following is a specification.

This invention relates to an internal combustion engine of that type in which the cylinders and pistons rotate about a stationary 10 crank shaft and relates more particularly to a two cycle explosion engine of this character possessing the advantage of simplicity, since no mechanically actuated valves are 15 necessary, and of a more even torque.

The invention has for one of its objects to improve and simplify the construction and operation of internal combustion engines of the type referred to, so as to produce a high 20 efficiency and to obtain a simple and effective control.

A further object of the invention is the employment of a separate fuel pump for each working cylinder whereby the charges 25 are delivered to the cylinders in a positive manner, the arrangement of the pump and working cylinders being such that a simple and substantial construction is produced.

A still further object of the invention is the 30 provision of a multi-throw crank shaft made up of sections so connected that the relative position of the pump pistons with respect to the pistons of the working cylinders can be changed, either while the engine is idle or in 35 operation, for effecting the discharge from the pumps to their respective cylinders at the proper period.

With these objects in view, and others, as will appear as the nature of the invention is 40 better understood, the invention comprises the various novel features of construction and arrangement of parts, which will be more fully described hereinafter and set forth with particularity in the claims appended hereto.

In the accompanying drawings, which illustrate certain of the embodiments of the invention, Figure 1 is a longitudinal section of one form of the invention. Fig. 1^a is a 50 fragmentary sectional view of the hinge connection between the two sections of the crank shaft of the engine. Figs. 2 and 3 are, respectively, a front elevation and a vertical-section of the fuel or mixture distributing

valve, drawn on an enlarged scale. Figs. 4 55 and 5 are, respectively, a front elevation and a vertical section of the inlet chamber associated with the distributing valve, drawn on an enlarged scale. Fig. 6 is a detail elevation of the spark timer. Fig. 7 is an end 60 view of the controller of the timer. Fig. 8 is a fragmentary side elevation of the engine showing the muffler of one of the cylinders and the means for completing the circuit of the individual spark plugs. 65

Corresponding parts in the several figures are indicated throughout by similar characters of reference.

Referring to the drawings, and more particularly to Fig. 1, 1 designates the side 70 bars of the supporting frame or yoke of the engine, on which bars the crank shaft 2 is supported in bearings 3. In the present instance, the crank shaft is of the two-throw type and made up of two substantially similar sections hinged or pivoted together, as by a pin 4 at their inner or crank arm ends. The left hand section 5 is held stationary on the supporting frame by a key 5'. The section 6 of the crank shaft is revolubly mounted in 80 the right hand bearing 3 for the purpose of changing the angular relation of the crank arms 7 and 8 to which are respectively connected the power and pump pistons. At the outer end of the section 6 is provided an 85 adjusting lever 9 whereby the said section can be shifted one way or the other about its axis for the purpose of varying the period of discharge from the pump or pumps to the working cylinder or cylinders or to reverse 90 the engine. The friction between the parts of the hinged joint of the shaft sections may be sufficient to hold the section 6 in any adjusted position. If desired, however, a suitable latch or locking device may be used in 95 connection with the operating lever 9 for holding the same stationary, as will be readily understood.

Each power or working cylinder 10 has associated with it a pump cylinder 11, the two 100 being preferably formed as a single casting and having a common removable head 12. The cylinder castings, of which there are two in the construction shown in Fig. 1, are detachably secured at the open ends of the 105 cylinders to the crank casing 13, the said casting being provided with hubs 14 through which the crank shaft extends. By this ar-

arrangement, the entire structure of the engine, save the crank shaft, is adapted to be rotated by the impulses resulting from the explosions in the several working cylinders. The 5 working cylinders 10 are arranged in a common plane, as are also the pump cylinders, so that the working pistons 15 are connected to a common crank pin. The pump pistons 16, which, like the working pistons, are of the 10 trunk type, are also connected to a common crank pin. The connection of the piston rods with the crank pins in this double opposed engine may be of any approved construction.

15 In the wall of each pump cylinder is cored out, or otherwise formed, a longitudinally extending conduit 17 which at its outer end communicates with the pump cylinder through a passage 18 in the head 12 and 20 which at its inner end communicates with the mixture inlet chamber through the passage 19 in the wall of the crank casing. The fuel mixture is drawn into each pump cylinder through an automatically actuated valve 20, and from the said cylinder the charge is 25 delivered to the working cylinder through a conduit 21 in the head 12, which conduit is controlled by the automatic valve 22. The crank pins are so related that the pump will 30 deliver a charge to its companion working cylinder at about the time the piston in the latter cylinder uncovers the exhaust port 23, and finish delivering the charge at about the time the exhaust ports are closed on the succeeding 35 return stroke. By reason of the crank shaft being made of two hingedly connected sections, the operative relation of each pair of pump and working pistons to produce the best effect can be determined with great 40 nicety.

The fuel mixture is supplied from a suitable carbureting system through a supply conduit 24 that discharges into an annular inlet chamber 25 formed in a washer or apertured plate 26. The annular member 26 is 45 assembled around the shaft section 6 and is held stationary, or rather prevented from rotating, by any suitable means, such as, the supply pipe 24. Intermediate the member 50 26 and the wall of the crank chamber having the passages 19, is a disk valve 27 that is keyed to the shaft section 6 so as to be angularly adjustable therewith. The valve 27, as clearly shown in Fig. 2, is provided with a 55 segmental port 28 through which the suction conduits 17 are periodically brought into communication with the inlet chamber 25. The port 28 is so proportioned as to properly 60 distribute the fuel mixture to the several pumps, so that the tendency of one pump robbing another is reduced to a minimum. This valve 27 is formed with a hub 29 which fits in the central opening 30 of the member 65 26, Figs. 3 and 5, so that the valve in said member will always be centralized. The

member 26 is held seated on the valve 27 and the latter is held against the crank chamber wall by the helical spring 31 disposed around the shaft section 6 and abutting at opposite ends, respectively, the member 26 and side 70 bar 3 of the supporting frame. By this arrangement, the parts are capable of relative rotation without the leakage of mixture. In an engine of the construction shown in Fig. 1, the charges are admitted to the working cylinders alternately, so that two equally spaced impulses are produced during each revolution. In an engine having a greater number of cylinders, the admission of the charges and the explosions take place in the successive 80 cylinders one after another.

In ordinary operation, the main piston or power crank is arranged at an angle of approximately 90° to the pump crank, and by turning the adjustable section of the crank 85 shaft which carries the pump crank through an arc of 180° the direction of rotation of the engine may be reversed. It is not, however, necessary, or in fact desirable, that the pump crank be at all times maintained at a right 90 angle to the working crank, and it is found in practice that the engine works best when the pump crank is located about 120° from the working crank, and if the two cranks are so relatively located, it will be necessary to 95 move the pump crank only through an arc of 120° to reverse the engine.

The correct angle of the pump crank with relation to the power crank can only be determined by running the engine. The angle is 100 not the same in all engines, a difference in diameter of cylinders, length of stroke, size of exhaust port, and number of revolutions per minute all tend to affect the correct position of the pump crank.

There is no predetermined position of the cranks, and the object of the adjustment is to permit finding of the correct position, and when this position is determined, to be able 105 to place the pump crank on the opposite side 110 of the working crank and in the same relative position thereto for reversing the engine.

Due to the fact that the cylinders are adapted to be rotated, a partial vacuum is 115 produced in the wake of each cylinder, and this fact is taken advantage of in the disposal of the exhaust gases, so that the discharge of the spent gases, in the partial vacuum thus formed in the atmosphere, assists materially in silencing the exhaust. Furthermore, the 120 gases are discharged from the rear side of each cylinder so that as they forcibly issue into the atmosphere, an impulse is given to the engine which is in a direction to assist the rotation of the latter, thereby adding power 125 to the engine. For this purpose, each cylinder is formed with an exhaust compartment 32 which may be preferably cast integral therewith, and is arranged at the exhaust port 23, as shown in Fig. 8, so as to receive 130

the products of combustion directly from the latter. The wall of the muffler compartment 32 is perforated with a number of rearwardly discharging jet openings 33 by which the exhaust gases are ejected into the atmosphere in the wake of the engine cylinders, it being assumed that the engine is rotating in the direction indicated by the arrow in Fig. 8. With the muffler arranged in this manner at each cylinder, the exhaust is conveniently disposed of without the need of a complicated system of discharge conduits, and with the advantage of increased power of the engine and a substantially noiseless exhaust 15 of the gases.

The igniting devices may be of any suitable character and in the present instance each working cylinder is provided with a 20 sparking plug 34 and each plug carries a collector or brush 35 that is adapted once in every revolution to pass into engagement with a contact 36. The contact 36 is in the form of an elongated plate curved in an arc and supported by an insulating block 37. 25 One wire of the high tension side of the ignition system is connected with the contact 36, as indicated at 38, and the other is suitably grounded on the engine structure.

Coöperating with the mechanism for electrically connecting the sparking plug to the circuit is a timer, more clearly shown in Fig. 6. This comprises a controller 39 formed of a disk of insulating material having a plurality of equally spaced metallic blocks 40 seated in the periphery thereof. The blocks 40 are grounded on the engine by means of wires 41 extending from the blocks to the hub of the crank casing. Arranged to make contact with the controller blocks is an arm 42 having an anti-friction roller 43 that bears on the periphery of the controller. The arm 42 is pivoted on a lever 44 that is supported on and insulated from the side bar 1 of the supporting frame adjacent the controller. The 45 spring 45 anchored at one end on the timer lever 44 bears at its free end on the arm 42 to maintain the metallic roller 43 in engagement with the controller. One side of the low tension or primary side of the ignition 50 system is grounded on the lever 44, so that the primary current passes from the battery or other source and induction coil, through the wire 46, the lever 44, arm 42, roller 43, controller 39 and the engine back to the battery.

Power is taken from the engine by a pulley and belt, a gear mechanism including a clutch, if desired, or any other suitable means. The pulley or gear is preferably keyed to the 60 left hand hub 14 of the crank casing. In the present instance, the gear wheel 47 is shown. Since the cylinders of the engine are adapted to rotate, it will be found that the fly wheel effect of the cylinders will, in most cases, be 65 sufficient, so that a separate fly wheel will not

be necessary, although it is obvious that a fly wheel may be used, if desired.

In connection with an engine of the character described, a special form of lubricating system is required in order that the various working parts may be satisfactorily lubricated. Since the cylinders and pistons rotate around the stationary crank shaft, it is preferable to supply the lubricant under pressure by a pipe 74, Fig. 1, to a conduit 75 extending through the crank shaft, the crank arms and pins. Branches 76 supply lubricant to the bearings 14 of the engine. The crank pins are provided with branch conduits 77 that register with conduits 78 extending longitudinally of the piston rods. These conduits 78 communicate with conduits 79 in the wrist pins 80 of the pistons. The pistons are apertured in line with the conduits 79, so that lubricant can be supplied to the walls of the pump and working cylinders. Sufficient lubricant flows out of the conduits 77 and 79 to lubricate the crank pin and the wrist pin bearings. By this arrangement, the cylinders, wrist pins, crank 90 pins, and bearings of the crank shaft are effectively lubricated from a single forced feed device. Although a lubricating system is not shown in the modified form of engine, depicted in Figs. 9 and 10, it is to be understood that a suitable lubricating system is to be employed.

I have described the principle of operation of the invention, together with the apparatus which I now consider to be the best embodiment thereof, but I desire to have it understood that the apparatus shown is merely illustrative, and that such changes may be made, when desired, as are within the scope of the invention.

What is claimed is:—

1. The combination with an internal combustion engine comprising a crank shaft, a cylinder mounted to revolve about the shaft, a piston in the cylinder connected with the shaft, and a support for the crank shaft, of a device revoluble with the cylinder for forcing the fuel charges thereto, and a mechanism arranged to control said device for varying the time of discharge of the fuel charges and for changing the direction of rotation of the cylinder.

2. The combination of a working cylinder, a piston therein, a pump cylinder, a piston therein, a crank shaft composed of two relatively movable sections, separate means for connecting the work piston with one section and the pump piston with the other section, and a device for changing the relative position of the said sections.

3. The combination of a working cylinder, a piston therein, a pump cylinder, a piston therein, means for rotatably mounting the cylinders, a stationary means to which one of the pistons is connected, and a stationary

means relatively adjustable with respect to the first mentioned means and connected with the other piston for varying the stroke of one piston with respect to the other.

- 5 4. The combination of a working cylinder, a piston therein, a pump cylinder, a piston therein, means for rotatably mounting the cylinders, a two-part crank shaft, a connection between the working piston and one part 10 of the shaft, a connection between the pump piston and the other part, means for holding one of the parts stationary, and a device for angularly adjusting the other part.
5. The combination of a plurality of cylinders, pistons therein, and a crank shaft made 15 of two parts and having crank pins to which the pistons are connected, and means for hingedly connecting the two parts of the crank shaft.
- 20 6. The combination of a crank shaft made of two parts and having a crank pin on each part, a plurality of cylinders mounted to revolve about the crank shaft, pistons in the cylinders connected with the crank pins, 25 means for holding one part of the crank shaft stationary, and a device for adjusting the other part of the crank shaft so as to change the angular relation of the crank pin thereof with respect to the crank pin on the stationary part.
7. The combination of a crank shaft made 30 of two parts and having a crank pin on each part, a plurality of cylinders mounted to revolve about the crank shaft, pistons in the cylinders connected with the crank pins, and a hinged connection between the parts of the shaft for permitting of relative angular adjustment of the crank pins.
- 35 8. The combination with a crank shaft, of

a plurality of cylinders mounted to revolve 40 around the crank shaft, said crank shaft being made of two parts and having a plurality of crank pins, pistons in said cylinders connected with the said pins, a device for holding one of the parts of the shaft stationary, means for adjusting the other part of the shaft about its axis, and a device for hingedly connecting the adjacent ends of the parts.

9. The combination of a plurality of working cylinders, a plurality of pump cylinders, 45 pistons in the cylinders, a crank shaft composed of two relatively adjustable parts, connections between the working pistons and one of the parts, connections between the pump pistons and the other part of the crank 50 shaft, and means for adjusting the position of the parts.

10. The combination of a working cylinder and a pump cylinder mounted to revolve, a stationary crank shaft made of two parts 55 which are relatively adjustable, pistons in the cylinders connected with the crank shaft, a suction conduit for the pump cylinder which extends from a point adjacent the crank shaft to the head of the latter, an inlet 60 chamber adjacent the crank shaft for supplying a fuel mixture to the suction conduit, and a valve keyed to the adjustable part of the crank shaft for controlling the supply of mixture to the conduit.

In testimony that I claim the foregoing as my own, I have hereto affixed my signature in the presence of two witnesses.

ROY CLIFTON MARKS.
